[57] CLAIM

The ornamental design for a firescreen, substantially as
shown and described.

DESCRIPTION

FIG. 1 is a perspective view of a fire screen showing my
new design;

FIG. 2 is a front elevational view thereof shown on a
slightly larger scale;

FIG. 3 is right side elevational view thereof; and
FIG. 4 is a bottom plan view thereof.

The pattern shown fragmentarily on the four front pan-
els is understood to repeat uniformly across the entire
indicated area. The rear of the device is completely
open and includes no additional portions not shown in
the drawings.
